[57] CLAIM

The ornamental design of a roaster, substantially as shown and described.

DESCRIPTION

FIG. 1 is a top front and right end perspective view of a roaster, showing my new design;

FIG. 2 is a top plan view thereof;

FIG. 3 is a front elevational view thereof, the rear view being a mirror image thereof;

FIG. 4 is a right end elevational view thereof, the left end view being a mirror image thereof;

FIG. 5 is a fragmentary cross-sectional view thereof, taken on line 5—5 of FIG. 2;

FIG. 6 is a fragmentary cross-sectional view thereof, taken on line 6—6 of FIG. 2;

FIG. 7 is a fragmentary cross-sectional view thereof, taken on line 7—7 of FIG. 2;

FIG. 8 is a fragmentary cross-sectional view thereof, taken on line 8—8 of FIG. 2;

FIG. 9 is a fragmentary cross-sectional view thereof, taken on line 9—9 of FIG. 6;

FIG. 10 is a fragmentary cross-sectional view thereof, taken on line 10—10 of FIG. 6;

FIG. 11 is a cross-sectional view thereof, taken on line 11—11 of FIG. 2;

FIG. 12 is a top plan view of a second embodiment of that shown in FIG. 1;

FIG. 13 is a cross-sectional view thereof, taken on line 13—13 of FIG. 12;

FIG. 14 is a bottom plan view of that shown in FIG. 1; and

FIG. 15 is a bottom plan view of that shown in FIG. 12. The front and rear elevational views and the right and left end elevational views of the second embodiment shown in FIG. 12 are identical to said elevational views shown in FIGS. 3 and 4, respectively.
